(57) **CLAIM**

The ornamental design for a clasp for watch bracelet, as shown and described.

DESCRIPTION

FIG. 1 is a front elevational view of a clasp for watch bracelet showing my new design;

FIG. 2 is a back elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front, top, right side perspective view thereof;

FIG. 8 is a back, top, left side perspective view thereof;

FIG. 9 is a back, top, left side perspective view of the clasp for watch bracelet, as shown in relation to a watch band in an exemplary operational position; and,

FIG. 10 is a back, bottom, right side perspective view of the clasp for watch bracelet, as shown in relation to the watch band in the exemplary operational position.

The broken lines in the drawing figures form no part of the claimed design.
